UNITED STATES PATENT OFFICE.

ALMAR E. WESTMAN, OF FENTON, MICHIGAN, ASSIGNOR OF ONE-FOURTH TO CHARLES H. LEA, ONE-FOURTH TO GUSTAF ALEXANDER OLOFSON, AND ONE-FOURTH TO CHARLES OLOFSON, ALL OF FENTON, MICHIGAN.

GRINDING MACHINE.

Application filed April 2, 1921. Serial No. 453,167.

To all whom it may concern:

Be it known that I, ALMAR E. WESTMAN, citizen of the United States, residing at Fenton, county of Genesee, State of Michigan, have invented a certain new and useful Improvement in Grinding Machines, and declare the following to be a full, clear, and exact description of the same, such as will enable others skilled in the art to which it pertains to make and use the same, reference being had to the accompanying drawings, which form a part of this specification.

The object of my invention is to provide a grinding machine of simple, durable and inexpensive construction.

A further object of my invention is to provide such a machine in which the grinding member or wheel is reciprocated as well as rotated so that the work may be more uniformly operated upon and so that the grinding wheel itself may last longer.

A further object of my invention is to provide an improved drive whereby the grinding wheel may be rotated and reciprocated at the same time from the same drive shaft while the rigidity of the machine is retained.

A further object of my invention is to provide a machine having a reciprocating head in which is mounted a non-slidable spindle so that great rigidity may be secured thereby and to provide in connection with this driving head means for removing the dust and for protecting the moving parts from the dust where necessary.

A further object of my invention is to provide an improved driving means for reciprocating the grinding head and means for varying the speed of the grinding spindle relative to that of both the drive shaft and the shaft which causes reciprocation of the grinding head.

With these and other objects in view, my invention consists in the arrangement, construction and combination of the various parts of my improved machine as stated in the objects, described in the specification, and shown in the drawings, in which:

Figure 1 shows a side elevation of my improved machine, parts being shown in section to better illustrate the construction.

Fig. 2 shows a front elevation thereof.

Fig. 3 shows a top or plan view thereof, the work supporting table being partly removed to better illustrate the construction, and,

Fig. 4 shows an enlarged detail sectional view illustrating a portion of the mechanism for reciprocating the grinding head.

Referring to the accompanying drawings, I have used the reference numeral 10 to indicate generally a substantially square base member having an extension 11 at the rear thereof which supports spaced bearings 12 and 13. Journaled in the bearings 12 and 13 is the main drive shaft 14 which carries spaced sets of pulleys 15 and 16. The sets of pulleys each include two pulleys of different diameters in the drawings, but more may be used if desired.

At the top of the stand 10, a pair of shelves 17 project laterally and form a support to which a casting 18 is secured. The casting 18 is designed to form the support for the work-supporting platform or table 19 and guides are also formed therein to carry the reciprocating grinding head. The guides shown in the drawings consist of what may be termed a keyway illustrated at 20 and which may, if desired, be so arranged that one side is detachable to permit ready removal of the grinding head therefrom. Such an arrangement is illustrated by the use of the strip 21 which is secured by the screws 22 to the casting 18 and provided with inclined faces to conform to the shape of the co-acting portion of the grinding head and to permit taking up any wear by tightening the screws 22.

The grinding head itself comprises a body member 23 having inclined edges designed to coact with the guiding portions 20 of the casting 18 to permit vertical reciprocation of the grinding head and it also has lugs 24 and 25 extending forwardly therefrom to form supports for the grinding spindle. Ball bearings 26 or other suitable bearing members may be inserted in the lugs 24 and 25 to support the grinding spindle 27. Between the bearings 26 and between the lugs 24 and 25 a pulley 28 is secured to the grinding spindle and a grinding wheel 29 is secured to the spindle above the upper bearing 26. Between the grinding wheel 29 and

the bearing 26 a shoulder is formed in the spindle and a dust petticoat 30 is forced onto the spindle so that the top of the petticoat is contiguous with the lower surface of 5 the shoulder mentioned. The upper lug 25 is preferably provided with an upwardly extending annular flange on its upper surface and around the upper bearing 26. The dust petticoat is preferably provided with a 10 downwardly extending flange at its outer edge which is disposed just outside of the flange on the lug so that when the grinding spindle is rotated, then the dust from the grinding will be caught by the petticoat 15 or thrown clear by it so that such dust will not get into the bearing 26. As the lower bearing 26 is below both the pulley 28 and the lug 25, it will be seen that practically none of the grinding dust can get into either 20 of these bearings to thereby injure the bearings. A dust cover 30^a is shown as being secured to the lugs 24 and 25 to protect the inner bearings from the dust produced by the grinding member.

23 Extending rearwardly from the stand 10 near the top thereof is a shelf 31 which supports at its rear end a bearing 32. A bracket 33 has a forwardly extending stub 34 formed thereon which enters the bearing 32 and is 28 held from movement therein when desired by a set screw 35. The bracket 33 has idler pulleys 36 at either end thereof and a belt 37 is extended around one of the pulleys 16 over the idler pulleys 36 and around the 35 spindle pulley 28. In this connection it may be mentioned that the body portion of the grinding head has a central opening there-through so that the belt may pass there-through. From the foregoing, it will be 40 seen that rotation of the drive shaft 14 will impart rotation through belt 37 to the spindle pulley 28 and consequently to the spindle. The tension on the belt 37 may be adjusted and equalized by tapping on either 45 the bracket 33 or the stud 34 to move the latter in the bearing 32, thereby adjusting the position of the idler pulleys 36. When the desired tension on the belt is secured then the set screw 35 may be tightened to 50 prevent the parts from slipping out of adjustment.

Extending from one side of the stand 10 in position below the shelves 17 are a pair of ears 38 which form bearings for a shaft 39. The shaft 39 carries a pair of contiguous pulleys 40 of different diameters in position where a belt 41 may be placed over the pulleys 15 and 40 to drive the shaft 39 from the drive shaft 14 at the desired speed. 55 The shaft 39 carries a relatively small gear 42 which in turn co-acts with a relatively large gear 43 mounted on a shaft 44 which is parallel with the shaft 39 and journaled at substantially the center of the stand 10. 60 Fixed to the shaft 44 is an eccentric 45. A

pair of spaced ears 46 are extended downwardly from the bottom of the body 23 of the grinding head and carry a wrist pin 47 to which one end of a connecting rod 48 is pivotally connected. The lower end of the 70 connecting rod 48 is provided with a semi-circular portion 49 designed to form half of an eccentric strap. The other member 50 of the eccentric strap is secured to the portion 49 by bolts 51 which extend through ears at 75 the ends of the two portions of the eccentric strap and the strap itself is designed to embrace the eccentric 45. The latter may, if desired, be provided with outwardly extending 80 annular flanges at its edges so that the eccentric is received within a channel. Shims 53 may be placed between the portions of the eccentric strap for the purpose of adjusting it to take care of any wear so that the operation of the eccentric may be as free 85 from vibration as is possible. Supported by the casting 18 is the work table 19 and the latter carries a dust hood 54 which covers the rear half of the grinding wheel 29. Extending rearwardly from the dust hood 54 is 90 a tube 55 through which air may be drawn so that the major portion of the dust formed by the grinding operation may be drawn away from the machine through this tube 55. In this connection it will be noted that the 95 work supporting table 19 may, if desired, be pivotally mounted on studs 56, carried by the casting 18, so that the work table may be inclined at an angle. Such a structure would, of course, include means for locking 100 the table in any desired position.

Among the many advantages of my improved device it is especially pointed out that it is so constructed that the parts are very rigid and vibration is reduced to a minimum. This is very important in a grinding machine of this type as vibration of the machine will tend to make the work of the grinding wheel irregular, besides causing undue wear on the parts. It may also be 110 mentioned that the speed of rotation may be varied to the speed of reciprocation and that means are provided for protecting the moving parts where necessary against injurious dust.

115 Some changes may be made in the construction and arrangement of the various parts of my device without departing from the spirit of my invention and it is my intention to cover such changes in the following claim.

What I claim is:

In a grinding machine, an upright frame, a bearing block rigid with the frame having a vertical guide-way for a grinding head, a grinding head having a body portion mounted in said guide-way for vertical movement and offset spaced-apart arm portions having bearings for a spindle, the uppermost arm portion provided with an upwardly-extend- 125 130

ing annular flange concentric said spindle bearing, a spindle journaled vertically in said arm portions for rotation extending upwardly above the upper arm, said spindle provided with a shoulder above the upper arm, a dust cap carried by said spindle encircling the same below said shoulder and

having a downwardly-extending flange freely encircling the upwardly-extending flange of the upper arm.

In testimony whereof, I sign this specification.

ALMAR E. WESTMAN.
